UNITED STATES PATENT OFFICE.

ANTON DVORAK, OF BERWYN, ILLINOIS, ASSIGNOR TO BEARDSLEE CHANDELIER MANUFACTURING COMPANY, OF CHICAGO, ILLINOIS, A CORPORATION OF DELAWARE.

DESIGN FOR A FINIAL FOR LIGHTING FIXTURES OR LAMPS.

Application filed April 2, 1923. Serial No. 5,630. Term of patent 7 years.

To all whom it may concern:

Be it known that I, ANTON DVORAK, a citizen of the United States, residing in Berwyn, in the county of Cook and State of Illinois, have invented a new, original, and ornamental Design for a Finial for Lighting Fixtures or Lamps, of which the following is a specification, reference being had to the accompanying drawing, which forms a part hereof.

My invention relates to a finial adapted to be employed either at the top of a portable lamp, or at the bottom of a lighting fixture.

In the drawing:—

Figure 1 is a top view of a finial with my new design.

Figure 2 is a side elevation of same.

Figure 3 is a perspective view thereof.

I claim:—

The ornamental design for a finial for lighting fixtures or lamps as shown.

ANTON DVORAK.
